UNITED STATES PATENT OFFICE.

JOHN D. RIPSON, OF PEPPERELL, MASSACHUSETTS.

FIREPROOF STRUCTURE.

No. 840,011.

Specification of Letters Patent.

Patented Jan. 1, 1907.

Application filed September 30, 1904. Serial No. 226,609.

To all whom it may concern:

Be it known that I, JOHN D. RIPSON, a citizen of the United States, residing at Pepperell, in the county of Middlesex and State of Massachusetts, have invented an Improvement in Fireproof Structures, of which the following description, in connection with the accompanying drawings, is a specification, like characters on the drawings representing like parts.

This invention has for its object to lessen the liability of fires, and especially in doors and door-casings.

In accordance with my invention I have covered a door and door-casing with metal, each side of the door being made in a single piece of sheet metal interlocked in the manner to be described, and the door-casing is also formed of several pieces of sheet metal interlocked at their edges.

Figure 1 in elevation shows a door and door-casing protected by metal in accordance with my invention; and Fig. 2 is a horizontal section through the door, on an enlarged scale.

The building is supposed to be of brick or steel covered with fireproof mortar.

The structure, referring to Fig. 2, is protected in the doorway by a metallic door-casing, shown as composed of three pieces $a a' a''$, the two pieces a and a' being substantially of the same shape, each being connected with the structure by suitable screws, or it might be rivets, and each having one edge bent to form a pocket, in each of which may be forced one of the like lips 2 of the piece a' , having the shoulder 3, constituting the door-jamb.

The door B is composed of outer and inner one-piece faces $b b'$, preferably of metal, struck into shape in a press to leave sunken panels. The outer and inner sheet-metal faces are united about their side and top and bottom edges by like metallic edging-pieces b'' , made as troughs, the central part 4 of the troughs forming the finish for the edges of the door, while the parallel flanges 5 receive against them the inner sides of the door-faces, as shown in Fig. 2.

Between the flanges 5 I have shown tubular distance-pieces 6, and through the inner and outer faces $b b'$, the flanges 5, and each tubu-

lar distance-piece I insert a rivet 7, the ends of which are upset, as at the right, Fig. 2. Any desired number of these tubes and rivets may be used and at any desired distance 55 apart, the more rivets used the more solid the door.

I insert at about the center of the width of the door a brace d , which may be shaped as shown in Fig. 2 or of some other suitable 60 shape, and near said brace I insert rivets 8.

Preferably the space between the two sheet-metal plates or faces $b b'$ will be filled in by wood, as shown by dotted lines e , the thickness of the wood being equal to the space 65 between one and the opposite panel, and the spaces between the wood and the inner sides of the faces $b b'$ I may, and preferably will, fill with asbestos or some other usual fire-resistant material, as at f .

The door is hung on usual hinges h .

Having described my invention, what I claim as new, and desire to secure by Letters Patent, is—

1. A door comprising metallic faces, metallic edging-pieces of substantial U shape in cross-section inserted between said faces at the edges of the door, tubular distance-pieces between the sides of the U-shaped edging-pieces, rivets extending through the faces, 80 sides of the edging-pieces and tubular distance-pieces, a brace or distance-piece extending from the top to the bottom of the door along its median line between the faces, another brace or distance-piece extending 85 from one side edge to the other side edge of the door, and rivets adjacent said braces connecting the faces.

2. A door-casing composed of two metallic pieces to overlie the sides of the wall of the building, each piece having a groove or pocket, and a third metallic piece provided with a jamb and having its edges received within said pockets.

In testimony whereof I have signed my 95 name to this specification in the presence of two subscribing witnesses.

JOHN D. RIPSON.
